UNITED STATES PATENT OFFICE.

FRANK CONSOLI, OF BROOKLYN, NEW YORK.

CUTTING MACHINE.

Application filed October 25, 1924. Serial No. 745,775.

This invention relates to cutting machines principally adapted for use in cutting a plurality of transverse open ended segmental grooves in the outer or upper face 5 of the finger board of stringed musical instruments, such as a violin, viola, cello or bass violin.

United States Letters Patent on finger boards of this type have been granted to me 10 October 25th, 1910, No. 973,719 and February 2nd, 1915, No. 1,126,957 and it is the general object of this invention to cut at the proper depth and at predetermined distances from each other, all of the grooves in such 15 a finger board in one operation.

With this and other objects in view the invention consists in the novel details of construction and combination of parts more fully hereinafter described and particularly 20 pointed out in the claims.

An embodiment of the invention is illustrated in the accompanying drawings, in which Figure 1 is a top plan view of the cutting machine.

25 Figure 2 is a longitudinal sectional view of the cutter per se. Figure 3 is a cross sectional view of the machine and finger board holder in position. Figure 4 is a detail perspective view of the finger board holder. Figure 5 is a detail perspective view of a violin finger board cut on the machine. Figure 6 is a cross sectional view taken on the line 6-6 of Figure 5, and Figure 7 is a perspective view of one of the celluloid cross pieces for filling the transverse segmental grooves.

As set forth in my previous patents, transverse grooves in the outer face of the finger board of a violin, viola, cello or bass violin 40 are filled with cross pieces, such as white celluloid to form a marked contrast to the finger board. These cross pieces correspond to the chromatic scale of such musical instruments and thus facilitate the operation of 45 locating the various notes and positions on the finger board for the composition of music.

Referring now to the drawings in detail, the machine for cutting these grooves comprises a top or table 1 supported by legs 2, a rotary cutter 3 and a holder 4 for holding 50 the finger boards to be cut.

Bearings 5 are provided on each end of the table for holding the shaft 6 and on one 55 end of the shaft is mounted a pulley 7 over which is trained a belt 8 for driving the

shaft from an electric motor 9, as shown in Figure 3.

The cutter 3 is mounted on the shaft and may be secured thereto in any well known 60 manner, such as by means of a key 10 and to facilitate the removal and replacement the cutter is preferably made in one complete unit as shown in Figure 2. It comprises a sleeve 11 having one end provided 65 with an enlarged shoulder portion 12, against which fits an end piece having a stop plate 13. A plurality of circular disc saws 14 are mounted on the sleeve and held in spaced relation at predetermined distances 70 from each other by collars 15. The other end portion of the sleeve is screw threaded as at 16 to receive clamping nuts 17 for holding the saws and spacing collars in a rigid position on the sleeve. 18, 19 and 75 20 designate gauge pieces mounted on the cutter for limiting the depth of cut when the machine is in use.

In the embodiment of cutter shown in the drawings, the number of saws and the distance between the adjacent saws is that which is required for cutting the finger board to produce the chromatic scale of a violin (see Figure 5). But it will be understood that in the finger boards of musical 80 instruments larger in size than the violin, such as the viola, cello or bass the number and spacing apart of the saws will be carried out in proportion to the size of the particular finger board to be cut.

When it is desired to use a larger cutter the smaller cutter can be removed by first disengaging the shaft from its bearings and then removing the cutter from the shaft and replacing it by the larger one, as is obvious. 95

The holder 4, for holding the finger boards to be cut, is preferably formed of a T shaped block of wood 21 and its face portion is provided, throughout its entire length, with a tapering groove portion 22 100 for receiving the finger board.

The finger board is securely wedged within the groove, and the upper or small end of the board may project slightly beyond the holder so as to engage the side of the stop plate 13 which acts as a guide piece during the cutting operation.

As shown in Figures 1 and 3 the front portion of the table 1 is restricted or cut away, as indicated at 23, so as to provide an 110 abutment upon which the holder is adapted to slide.

During the cutting operation an operator 5
grips the holder between his fingers by the
handle portion 24 and holds the lower portion
of the holder against the abutment and
then moves the lower edge of the finger
board into engagement with the saws. During
the cutting of the grooves the operator
swings the holder in front of the cutter and
at the same time presses it against the abut-
ment along which it slides at right angles
to the axis of the cutter.

By reason of the curvature of the upper
face of the finger board and its engagement
with the gauge pieces 18, 19 and 20 a plu-
rality of segmental transverse open ended
grooves 25 are cut in the upper face of the
finger board in a single operation.

Modifications of the arrangement shown
may be made if desired. For instance in-
stead of the holders being operated at the
side of the cutter it could be made to oper-
ate between guide pieces from the top of the
cutter.

What is claimed as new is:

- 25 1. A cutter comprising a group of circu-
lar saws united in parallel relation and
spaced apart to correspond to the chromatic
scale of a violin finger board, and means for
rotating the cutter in combination with a
holder for the finger board adapted to be
swung in front of said cutter and an abut-
ment for said holder upon which the holder
may be slid when holding the finger board
in contact with said saws, said holder hav-
ing a convex edge adapted to be slid and
rocked on said abutment.
- 30 2. A cutter comprising a group of circu-
lar saws united in parallel relation and
spaced apart to correspond to the chromatic
scale of a violin finger board, and means for
rotating the cutter in combination with a
holder for the finger board having its face
portion provided with a tapering groove
into which the finger board is adapted to
fit, said holder adapted to be swung in front
of said cutter and an abutment for said
holder upon which the holder may be slid when
holding the finger board in contact with said
saws, said holder having a convex edge
adapted to be slid and rocked on said abut-
ment.
- 35 3. A cutter comprising a group of circu-
lar saws united in parallel relation and
spaced apart to correspond to the chromatic
scale of a violin finger board, a stop plate
55 on the end of said cutter and means for
rotating the cutter; in combination with a
holder for the finger board adapted to en-
gage the stop plate and to be swung in front
of said cutter and an abutment for said
holder upon which the holder may be slid
when holding the finger board in contact
with said saws, said holder having a convex
edge adapted to be slid and rocked on said
abutment.
- 40 4. A cutter comprising a group of circu-
lar saws united in parallel relation and
spaced apart to correspond to the chromatic
scale of a violin finger board, gauge pieces
70 mounted on the cutter for limiting the depth
of cut and means for rotating the cutter; in
combination with a holder for the finger
board, said holder having its face portion
provided with a tapering groove into which
the finger board is adapted to fit, said holder
adapted to be swung in front of said cutter
and an abutment for said holder upon which
the holder may be slid when holding the
finger board in contact with said saws, said
holder having a convex edge adapted to be
80 slid and rocked on said abutment.
- 45 5. A cutter comprising a group of circu-
lar saws united in parallel relation and
spaced apart to correspond to the chromatic
scale of a violin finger board, a stop plate
85 on the end of said cutter, gauge pieces
mounted on the cutter for limiting the depth
of cut and means for rotating the cutter; in
combination with a T shaped holder for the
finger board having its face 90 portion
provided with a tapering groove into which
the finger board is adapted to fit, said holder
adapted to swing in front of said cutter and
an abutment for said holder upon which the
holder may be slid when holding the finger
board in contact with said saws, said holder
having a convex edge adapted to be slid and
rocked on said abutment.
- 50 6. In testimony whereof, I have signed my
name to this specification this 23rd day of
October, 1924.

lai saws united in parallel relation and
spaced apart to correspond to the chromatic
scale of a violin finger board, a stop plate 55
on the end of said cutter and means for
rotating the cutter; in combination with a
holder for the finger board adapted to en-
gage the stop plate and to be swung in front
of said cutter and an abutment for said
holder upon which the holder may be slid
when holding the finger board in contact
with said saws, said holder having a convex
edge adapted to be slid and rocked on said
abutment.

4. A cutter comprising a group of circu-
lar saws united in parallel relation and
spaced apart to correspond to the chromatic
scale of a violin finger board, gauge pieces
70 mounted on the cutter for limiting the depth
of cut and means for rotating the cutter; in
combination with a holder for the finger
board, said holder having its face portion
provided with a tapering groove into which
the finger board is adapted to fit, said holder
adapted to be swung in front of said cutter
and an abutment for said holder upon which
the holder may be slid when holding the
finger board in contact with said saws, said
holder having a convex edge adapted to be
80 slid and rocked on said abutment.

5. A cutter comprising a group of circu-
lar saws united in parallel relation and
spaced apart to correspond to the chromatic
scale of a violin finger board, a stop plate
85 on the end of said cutter, gauge pieces
mounted on the cutter for limiting the depth
of cut and means for rotating the cutter; in
combination with a T shaped holder for the
finger board having its face 90 portion
provided with a tapering groove into which
the finger board is adapted to fit, said holder
adapted to swing in front of said cutter and
an abutment for said holder upon which the
holder may be slid when holding the finger
board in contact with said saws, said holder
having a convex edge adapted to be slid and
rocked on said abutment.

In testimony whereof, I have signed my 100
name to this specification this 23rd day of
October, 1924.

FRANK CONSOLI.
